PRINTING TELEGRAPH RECEIVER

Edward E. Kleinschmidt, Highland Park, Ill.

Application July 25, 1938, Serial No. 221,192

25 Claims. (Cl. 178—34)

This invention relates to telegraph receivers of the type in which the selections are controlled by a permutation code selecting mechanism and in particular, to improvements in the mechanisms disclosed in my applications #18,888, filed April 29, 1935, #95,883, filed Aug. 13, 1936, and #150,384, filed June 25, 1937.

The mechanism shown and described herein is particularly adapted to the selecting mechanism 10 shown in my aforesaid application #150,384.

The principal object of the invention is to provide simplified mechanisms for utilizing the first selective impulse to select from one of two groups of characters independently of the selective operations of the following selective impulses.

A further object of the invention is to provide means to permit a printing type wheel to rotate freely during the interval of its greatest acceleration which is accomplished by automatically interrupting the contact between an inking device and the type wheel during a certain period in the cycle of operation of the type wheel.

Still a further object is the provision of a novel selector lever and support therefor wherein the 25 disadvantages due to wear of prior devices are eliminated.

Further objects appear in the following description and in the appended claims:

In the telegraph receivers shown and described 30 in my application #18,888 it is necessary to rotate the stop wheel shaft at least two and one half times faster than the selecting shaft which, under high speed operation, is somewhat detrimental. The mechanism herein described overcomes this difficulty in a simple and direct manner by providing a mechanism that will use the first unit of the code to operate a selection to rotate the type wheel independent of the stop wheel, and in which the stop wheel selections will 35 start with the second unit of the code thereby giving more time for the stop wheel to assume its normal start position after a previous printing operation as well as to increase the time during which the type wheel makes its initial 180 degree turn.

In my application #150,384 it is proposed to 40 reduce the high speed of rotation of the stop wheel and the type by providing a mechanism operated under control of the first unit of the code to shift the type wheel axially and to use the remaining units of the code to control the rotary selected position in progressive steps. While the proposed improvement is effective in its object to reduce the required speed of the 45 stop wheel and the type, it is not easily ap-

plicable to the mechanism shown in application #95,883 for selecting the operating bars of a typewriter, as well as for other uses where an axially movable recording device is not usable.

In the present invention the recording device 5 is not moved axially but is revolved one half turn under control of the first selective impulse, which occurs during the operating time of the following selective impulses and results in imparting a compound revolving action on the type 10 wheel or other recording device.

Referring to the drawings:

Figure 1 shows the apparatus in perspective, all of the framework being eliminated so as to show the parts more clearly.

Figure 2 is a detail of the sleeve for rotating the type wheel shaft by a camming action.

Figure 3 is a detail of the sleeve-operating mechanism shown in the operated position.

Figure 4 shows a mechanism for interrupting 20 the contact between the type wheel and its inking roller.

Figure 5 is a side view of a preferred modification of the selector lever of my invention and the bearing or support therefor.

Figure 6 is a plan of the lever of Figure 5.

Figure 7 is a side elevation of the typewheel rotating lever together with mechanism associated therewith.

Figure 8 is a side elevation of the release lever 30 together with mechanism associated therewith.

Figure 9 is a side view of part of the normal stop lever and associated parts.

Figures 10, 11 and 12 are side views of a selecting lever in several different operating positions.

Figure 13 is a side view of part of the armature and associated stop lever.

Referring now to Figure 1, gear 1, loosely mounted on shaft 2, is rotated in a clockwise direction at a constant speed by a motor 29, an idler gear 3 connects gear 1 with gear 4, also rotated in a clockwise direction and loosely mounted on shaft 5; gear 1 tends to rotate shaft 2 by a friction coupling 6, and gear 4 tends to rotate shaft 5 by a friction coupling 7. Shaft 2 40 has fixed on it a cam assembly 8 and an orientable stop member 9. Cam assembly 8 consists of a latch release cam 10, four stop lever cams 11, a normal stop lever cam 12, type wheel shift lever cam 13, and release lever cam 14. Latch release 45 lever 17 rotates on stud 15 and operates latch 16. Four stop levers 19 are mounted on stud 15 and each has an elongated bearing aperture 30, see Figs. 10, 11 and 12, which permits a slight lateral displacement as well as rotation on stud 15. Nor-

25

55

mal stop lever 18 rotates on stud 15, see Fig. 9. Type wheel rotating lever 21, also mounted on stud 15, has an elongated bearing aperture the same as stop levers 19 and is connected by pin 22 to the bifurcated end of lever 23. Release lever 24 rotates on stud 15 and bears against latch 25. Latch 16 and latch 25 rotate on stud 26 and are held in their unoperated positions by springs 27 and 28. Springs 31 hold stop levers 18 and 19 against the lower part of stud 15 and stop 32. Spring 33 holds type wheel shift lever 21 against the lower part of stud 15 and stop 32.

A receiving magnet 34 is connected by wires 35 in the circuit of a transmitter not shown. Armature lever 36 has a bearing on stud 37 and has attached to it latch plate 38 and fulcrum plate 39. Armature lever 36 when retracted by spring 41 rests against stop screw 42. A stop lever 43 pivoted on stud 44 lies in the path of stop member 9 and holds shaft 2 against rotation when they are in engagement. Pin 43 limits rotation of stop lever 43. Stop lever 43 has an extension 45 that rests on latch plate 38 when armature lever 36 is attracted, as shown in Figure 1. When armature lever 36 is released, under a no-current start condition, spring 41 pulls armature 36 to the left against stop 42. In this position hooked end 47 of extension 45 of stop lever 43 is moved off latch plate 38, see Fig. 13. Stop lever 43 is now disengaged from stop member 9 by spring 46, leaving shaft 2 free to rotate with gear 1 until lug 48 on stop member 9 engages with cam extension 49 of stop lever 43 to restore stop lever 43 to its normal position, as shown in Figure 1. In this position lever 43 is spaced slightly from stop 42. Stop levers 19 and type wheel rotating lever 21 are each provided with a bearing ledge 51. Stop levers 19 and normal stop lever 18 are each provided with stop extension 52 and latch extension 53, as shown in Figs. 1, 5, 10, 11 and 12. The upper end of latch 16 forms a bar 20 which extends across and engages all of the latch extensions 53 of stop levers 19 and of normal stop lever 18. Fingers 56 of stop wheel assembly 54 rotate in the path of stop extensions 52 of stop levers 19. Stop wheel assembly 54 provided with stops 56 over 180 degrees of its circumference is fixed to shaft 5 and comprises four rows of stop fingers each row of stops doubling in number over the previous row, the first row having one stop, the next two, the next four, and the last eight stops. One additional stop 55 is provided which engages with normal stop lever 18 in the normal stop position and holds shaft 5 against rotation, as shown in Figures 1 and 9. When armature lever 36 is moved against stop screw 42 it first releases stop lever 43 from engagement with orientable stop member 9, permitting shaft 2 and cam assembly 8 to rotate, as explained above. Cam 13 thereupon operates type wheel rotating lever 21 and thereafter the four cams 11 operate the four stop levers 19 in succession. If armature lever 36 remains against stop 42, levers 21 and 19 will pivot on latch 16, the elongated bearing aperture in the levers permitting them to move vertically without rotation on stud 15, Fig. 12. When, however, armature lever 36 is moved to the attracted position away from stop 42, after it has released stop lever 43, fulcrum 39 will be under bearing ledge 51 and if this happens when one of the stop levers 19 is operated by a cam 11, lever 19 will engage fulcrum plate 39 and pivot thereon, see Fig. 11, forcing its latch extension 53 to move latch 16 outwardly and in so doing latch 16 will release normal stop lever

18 permitting stop finger assembly 54 and shaft 5 to rotate. Stop extension 52 of the operated stop lever 19 will then be in the path of its row of stop fingers forming part of stop wheel 54 and will again stop shaft 5. The operated stop lever 19 will then become latched on latch 16 and remain there until the next stop lever 19 is operated which, when operated to fulcrum on fulcrum plate 39, will place its stop extension in the path of the stop wheel and release the previously set stop lever. Latch extension 53 will then rest on latch 16 and remain there until the next stop lever is operated to fulcrum on fulcrum plate 39 or until latch 16 is operated by latch release cam 10, which occurs at the end of 15 the cycle. By varying the operation of the four stop levers through the action of armature lever 36, stop wheel 54 and shaft 5 can be set in sixteen different positions including the normal stop position. The parts just described are the same and operate in the same manner as shown and described in my application #95,883 with the exception that in the present invention only four of the stop levers 19 control the positioning of stop wheel 54 and therefore 16 instead of 32 25 positions of the stop wheel are obtained and stop wheel 54 makes a maximum of one-half revolution during each selecting cycle. A somewhat more detailed explanation of the operation of stop levers 19 and stop wheel 54 is given in my 30 aforementioned application #95,883.

The parts described above are the same and bear the same reference numerals as in my aforementioned application #150,384. In that disclosure thirty-two selections were obtained by using 35 the first selective impulse to shift the printing to a second group of type. A shifting mechanism for the type wheel operated under control of the first unit of the code was provided to carry this idea into effect. In the present disclosure, as 40 shown in Figures 1, 2 and 3, thirty-two selections are obtained by rotating the type wheel through an arc of 180 degrees by a mechanism whose operation is controlled by the first selective impulse but operates independently of the remaining selective impulses. As in my application #150,384, this operation is controlled by a lever 21 and a release lever 24. The progressive stops are placed on only 180 degrees of the circumference of the stop wheel and only one normal stop 50 is provided, which is unlike the arrangement set forth in my application #150,384 wherein the stop wheel has two complete sets of progressive stops and two normal stops. In the present invention the type wheel 104 is provided with 32 55 possible printing positions about its circumference and makes one turn for each operating cycle including the stop for printing. The stop wheel 8 makes any of sixteen selections while it is revolving through an arc of 180°. After the printing operation it is released and continues to revolve until stop 55 engages with projection 52 completing one revolution. The parts cooperate in the following manner, lever 21 connects with shaft 57 through lever 23 which has fixed there- 60 to a lever 59 that terminates in an extension 60. A lever 61 pivoted on a universal bearing 62, is held in contact with the extension 60 of lever 59 by a spring 63. The opposite end of lever 61 is bent upward and carries a roller 64 that is 65 placed between flanges 65 of a sleeve 66 which is slidably and rotatably mounted on shaft 5 and shaft 67, the latter carrying type wheel 104. A pin 68, fast in shaft 5, works in a diagonally placed slot 69 in sleeve 66, and a pin 71, fast in 75

shaft 67, works in a diagonally placed slot 72 in sleeve 66. The slots 69 and 72 are so formed that when sleeve 66 is moved to the right along the shaft 5 and 67 against the tension of spring 73, shaft 67 is rotated 180 degrees with respect to shaft 5. In the operation of the device, shaft 5 is either rotated through the friction clutch 3 or is held stationary by stop 18 or one of the stops 19; shaft 67, being connected to shaft 5 by sleeve 66 and pins 68 and 71, rotates with shaft 5 as well as being rotated under the influence of the sliding motion of sleeve 66. The normal position of sleeve 66 is as shown in Figures 1 and 2, that is, when it is moved to the left under the influence of spring 73 and when pins 68 and 71 are at the right hand end of slots 69 and 72 respectively. A face cam 74 is fixed to shaft 2 and rotates therewith and lever 61 is engaged by cam 74 when placed in its path by the operation of lever 59. 20 As in my previous applications above referred to, it is intended to operate this telegraph receiver in circuit with a transmitter sending a no-current start impulse, five selecting impulses which may be either current or no-current according to the character transmitted, and a current stop condition. It is to be understood that this arrangement may be varied as desired and that the number of selecting impulses may be increased or reduced in accordance with the code 25 to be used.

The operation of the parts heretofore described is as follows:

The general operation of the selecting mechanism, which includes the parts shown in Figure 1 and numbered from 1 to 57, is described and explained in my application #150,384 in which the same parts bear the same reference numerals. The operation of levers 21 and 23 and shaft 57 by the first selective impulse through the joint action of magnet 34, armature 36, pivot 39 and cam 13, is also fully explained in application #150,384. To briefly repeat a description of the operation of the selecting mechanism: It is assumed that magnet 34 is connected in the circuit of a five-unit code start-stop transmitter and that shaft 2 when released is rotated in timed relation with the received signals, by gear 1 and friction clutch 6, and that shaft 5 is under rotative tension through friction clutch 7 and gears 4, 3 and 1 which are rotated by a motor 29. The normal stop current on the line holds armature 36 attracted and cam assembly 8 fixed to shaft 2 is held stationary by stop arm 43. When a group of signals are received on magnet 34 the first or start impulse, which is no current, releases armature 36, spring 46 then operates stop lever 45 to release cam assembly 8 and shaft 2 as explained above. The then following selective impulses operate armature 36 while cams 13 and 11 operate levers 21 and 19 in succession and in timed relation with the received signals. Cam 13 operates lever 21 during the time of the first selective impulse and cams 11 operate levers 19 in succession during the remaining selective impulses. The first lever 19 to be operated by the joint action of armature 36 and its cam 11, that is when lever 19 pivots on fulcrum plate 39 while it is being operated by its cam 11, operates the universal latch 16 and releases normal stop lever 18 from engagement with stop 55 forming part of stop wheel 54 which thereupon rotates and ultimately assumes its selected position in accordance with the successive operations and setting of stop levers 19. Before cam assembly 8 has made a complete revolution, cam 10 re-

leases the last set stop lever 19 and restores normal stop lever 18. The selected character is recorded during the time interval between the setting of the last lever 19 and the operation of cam 10 on release latch 16.

As in my application #150,384, the second, third, fourth and fifth selective impulses control the positioning of the stop wheel through an arc of 180 degrees in sixteen possible settings. Thirty-two selections are obtained by revolving the type wheel an additional 180 degrees under control of the first selective impulse during the time period of the following selective impulses which is accomplished in the following manner:

When the first selective impulse is of a nature to place fulcrum plate 39 under notch 51 of selector lever 21 when that is operated by its cam 13, lever 21 is moved to rotate shaft 57 through lever 23 and connecting pin 22, lifting lever 59 which is connected thereto. Fig. 7 shows lever 21 in this position and latched on latch 25. The extension 60 of lever 59 thereupon raises lever 61 into the path of cam 74 which then engages lever 61, operating it to move sleeve 66 along the shafts 5 and 67 through roller 64 and flanges 65, shafts 5 and 67 being held in bearings so they cannot move axially but are free to rotate. The operation of lever 61 by cam 74 and the movement of sleeve 66 along shafts 5 and 67 continues during the setting of stop wheel 54 and shaft 5 by the selective operation of the remaining four selective impulses. Lever 61 when operated, remains in engagement with cam 74 as shown in Figure 3, until the selected character is recorded.

In the present type of receiver wherein the selected character is recorded by printing from a typewheel which is inked by an ink roller, difficulty is experienced in rotating the type wheel with the added load of the ink roller, especially during the first part of the rotary selective period. To eliminate the added load of the inking roller during this interval I have provided a cam 101, Figure 4, operated in timed relation with the selector shaft 2, which acts on a lever 102 carrying the inking roller 103 to raise the inking roller from the typewheel 104 during the time of greatest acceleration of the typewheel.

In Figures 5 and 6 I have shown a preferred modification of stop lever 19 of Figure 1 including a novel support therefor that may also be employed with lever 21. While levers 19, as shown in Figures 1, 10, 11 and 12, which are provided with elongated apertures fitting about stud 15 as shown in detail in my application Serial No. 95,883 are satisfactory, the elongated aperture presents a small surface against the round stud 15 and therefore wears considerably. To eliminate such wear with its attendant disadvantages, I have provided a stop lever 19' with a rectangular aperture 105, the aperture preferably having rounded corners as shown at 106. The remaining elements of lever 19' correspond to those of levers 19 as shown by like reference characters. Aperture 105 is preferably of a size to receive a shoe 107, preferably of hardened steel squared with the corners removed at 108, and of a size to permit a sliding fit. By reason of the rectangular shape of aperture 105 and the square shape of shoe 107, lever 19 can be displaced relative to shoe 107 and stud 15 which supports shoe 107 by reason of aperture 108 which is of a size to permit shoe 107 to only rotate about stud 15. A recess 109 is preferably formed in each lever to accommodate the spring 76

secured thereto. This arrangement is particularly advantageous in not only eliminating wear on selector levers but also on stud 15.

Printing from the typewheel 104 may be effected in any desired manner as for example by a print hammer controlled by means on shaft 2. Likewise, mechanism for shifting the print hammer, or other printing means employed, to print from either of the two rows of type on the wheel 104 are provided. This mechanism may be of any desired type adapted to be controlled by function discs 110 carried by shaft 67. Neither the printing device or typewheel shifting mechanism form a part of the present invention and are hence not disclosed.

It is obvious that the typewheel 104 shown in Figure 1 may be replaced by one or more type bar selecting fingers, for example, as shown in my application #95,883, or that any other recording or indicating device or type selecting mechanism may be used in lieu thereof.

It is to be understood that the foregoing described mechanisms are capable of a wide variety of applications other than those described herein by way of illustration and that the invention is not limited to the particular arrangements described and that considerable modification or rearrangement of the parts is possible without departing from the invention, and that the scope 30 of the appended claims shall not be limited to the foregoing description but all changes which come within the meaning and range of equivalency of the claims are intended to be embraced therein.

35 What is claimed and desired to be secured by United States Letters Patent is:

1. A telegraph receiver comprising a single receiving magnet, a selecting mechanism responsive to a series of successive selective impulses received by said magnet and rotatable recording means controlled thereby, said selecting mechanism including means under the control of the first selective impulse for rotating the recording means 180 degrees and means under the control of the remaining selective impulses of said 45 series for selecting rotary positions of the recording means throughout 180 degrees.

2. A telegraph receiver in which the selection of characters is controlled by a permutation code selector comprising a recording device, a single magnet, a rotary stop member having rows of stops thereon that progressively double in number as to the rows, stop means actuated by said magnet under the control of all but the first unit of the code for directly and progressively positioning said rotary stop member, a rotary recording device connected to said stop member, and means under control of the first unit of the code for rotating said recording device independently of said stop member.

3. A telegraph receiver comprising rotatable recording means; magnetic receiving means responsive to a series of successive selective impulses; a selecting mechanism including, a rotary stop member for selecting rotary positions of said recording means throughout 180 degrees; means for selectively positioning said stop members under the control of all but the first selective impulse of said series, and means under control of the first selective impulse for rotating said recording means through an arc of 180 degrees during the operating time of the remaining impulses of said series.

4. A telegraph receiver comprising; a type 75 wheel having a plurality of groups of charac-

ters thereon; a permutation code selector capable of a plurality of successive selective operations; and means under control of the first unit of a code signal for rotating the type wheel independently of the selective operation of the 5 remaining units of said code signal.

5. In a telegraph receiver responsive to a permutation code in which the selective positioning is controlled by a stop wheel provided with stops that progressively double in number, and a 10 selecting mechanism for positioning the stop wheel progressively through an arc of 180 degrees in accordance with all but the first unit in said code; and means, under the control of the first unit in the code, for effecting independent selective 15 positioning through an arc of 180 degrees in one movement and during the time of the selective operation of the remaining code units.

6. A telegraph receiver comprising a receiving magnet, a permutation code selecting mechanism 20 controlled thereby and a stop wheel provided with stops that progressively double in number and arranged to be progressively positioned under the control of said selecting mechanism, a shaft for said stop wheel, a second shaft driven by 25 said stop wheel shaft, a type wheel on said second shaft, and connecting means between said shafts operable under control of the first unit in the code to rotate the type wheel shaft with relation to the stop wheel shaft. 30

7. A telegraph receiver responsive to a permutation code comprising, rotatable recording means connected to a stop wheel provided with rows of stops that progressively double in number; a selecting mechanism for controlling the positions 35 of the stop wheel in accordance with all but the first unit in the code; and means under control of the first unit in the code for shifting the recording means rotatably with respect to the stop wheel.

8. In a telegraph printer responsive to received signals, a type wheel, a stop wheel having rows of stops that progressively double in number as to the rows, an adjustable connection between said type wheel and said stop wheel, a 45 selecting mechanism to progressively stop the stop wheel in accordance with the received signals, and means to adjust said connection between said type wheel and said stop wheel to revolve the type wheel with respect to the stop wheel under the control of one of the units in 50 the code. 40

9. In a telegraph printer responsive to received signals, a receiving magnet, a selecting mechanism controlled thereby to position a stop wheel provided with rows of stops that progressively double in number in accordance with the received signals, a type wheel connected to said stop wheel, an inking roller for said type wheel, and means operated in timed relation with the received signals to permit contact between the inking roller and the type wheel only during selected intervals to thereby reduce the load on the typewheel during periods of its greatest acceleration. 60

10. A telegraph printer in which a type wheel 65 is positioned progressively to its final printing position, an inking roller for said type wheel, and means operated in timed relation with the progressive positioning of the type wheel to release the contact between the inking roller 70 and the type wheel to thereby reduce the load on the type wheel during periods of its greatest progressive steps.

11. A telegraph receiver comprising a receiv- 75

- ing magnet; a selecting mechanism responsive to a series of successive selective impulses; and recording means controlled thereby; said selecting mechanism including means under the control of one of said selective impulses for rotating said recording means through a part of a revolution and means, under the control of the remaining selective impulses and including stop means, for selecting rotary positions of the recording means throughout an additional part of a revolution.
12. A telegraph receiver in which the selection of character is controlled by a permutation code selector comprising a magnet, a rotary stop member having rows of stops thereon that progressively double in number as to the rows, stop means under the control of said magnet to directly and progressively position said rotary stop member under the control of all but one unit of the code, a rotary recording device connected to said stop member, and means under control of the remaining unit of said code to rotate said recording device independently of said rotary stop member.
13. A telegraph receiver comprising recording means arranged to rotate, magnetic receiving means responsive to a series of successive selective impulses, a selecting mechanism, a rotary stop member arranged to be selectively positioned by said selecting mechanism under the control of all but one of said impulses, and means under control of said one impulse to rotate said recording means through an arc of 180 degrees during the operating time of the remaining impulses.
14. In a telegraph printer responsive to received signals, a type wheel, a stop wheel, selecting mechanism to progressively stop said stop wheel in accordance with the received signals, and means to drive said type wheel from said stop wheel comprising a pair of aligned shafts, respectively secured to each of said wheels, a single sleeve mounted on each of said shafts and freely rotatable thereon with a pair of diagonal slots therein, and a pin on each of said shafts to engage said slots and secure said shafts in aligning relation.
15. In a telegraph printer responsive to a series of successive impulses, a type wheel, a stop wheel, selecting mechanism to progressively stop said stop wheel in accordance with certain of said impulses, shafts to support each of said wheels, said shafts being axially aligned, a sleeve connecting said shafts and freely rotatable thereon with diagonal slots therein, a pin on each of said shafts positioned to engage said slots, and means controlled by a remaining impulse to shift said sleeve axially on said shafts to vary the relative positions thereof.
16. In a printing telegraph receiver; printing means; stop means for positioning said printing means; a pivot; a series of selector members for said stop means; and a series of shoes rotatably supported on said pivot and arranged to support said selector member for both rotation and radial displacement.
17. The combination as claimed in claim 16 wherein each of said selector members are provided with a rectangular aperture and said shoes are formed substantially as a square with each side thereof substantially equal to the width of said aperture whereby said selector member can slide on said shoe through the length of said aperture.
18. In a telegraph printer, the combination set forth in claim 15, wherein said slots are in diagonally opposite position to rotate one of said shafts 180 degrees relative to the remaining shafts when said sleeve is shifted.
19. In a telegraph receiver, the combination set forth in claim 15, wherein means are provided for shifting said sleeve in synchronism with the operation of said selecting mechanism when the impulse for shifting said sleeve is received.
20. In a telegraph receiver responsive to a series of received signals, a stop wheel, selecting means to position said stop wheel in accordance with certain of said received signals, a type wheel, shafts to support said type wheel and said stop wheel, and means responsive to one of said received signals for rotating said type wheel shaft 180 degrees relative to said stop wheel shaft while maintaining a driving connection therebetween, said means comprising a single sleeve on the adjacent ends of said shafts, diagonally positioned pin and slot connections between each of said shafts and said sleeve, and means to shift said sleeve comprising a collar on said sleeve, a lever to engage said collar, a cam driven in synchronism with said selecting means, and means responsive to the character of one of said received signals to shift said lever into the path of said cam.
21. A telegraph receiver comprising a receiving magnet; a permutation code selecting mechanism controlled by said magnet; a stop wheel provided with stops that progressively double in number and arranged to be progressively positioned by said selecting mechanism; rotating type selecting mechanism positioned by said stop wheel; and additional means, operable under the control of permutation code selecting mechanism, for rotating said type selecting mechanism independently of said stop wheel.
22. A telegraph receiver comprising a receiving magnet; a permutation code selecting mechanism controlled by said magnet; a stop wheel provided with stops that progressively double in number and arranged to be progressively positioned throughout an arc of 180 degrees by said selecting mechanism; a rotatable member positioned by said stop wheel; and separate means operable under control of said permutation code selecting mechanism, for rotating the rotatable member through an arc of an additional 180 degrees.
23. A telegraph receiver comprising a receiving magnet; a permutation code selecting mechanism controlled by said magnet; a stop wheel provided with stops that progressively double in number and arranged to be progressively positioned by said selecting mechanism; a rotatable member positioned by said stop wheel; and separate means, operable under control of said permutation code selecting mechanism, for rotating the rotatable member through an arc of 180 degrees during the operating period of said selecting mechanism.
24. A telegraph receiver comprising a receiving magnet; a permutation code selecting mechanism controlled by said magnet; a stop wheel provided with stops that progressively double in number and arranged to be progressively positioned by said selecting mechanism; a rotatable member positioned by said stop wheel; and independent means, initiated by said permutation code selecting mechanism in response to one of the code signals of a group, for starting an independent rotary movement of said rotatable member.
25. A telegraph receiver comprising a receiving

magnet; a permutation code selecting mechanism controlled by said magnet; a stop wheel provided with stops that progressively double in number and arranged to be given a progressive rotary movement by said selecting mechanism; a rotatable member positioned by said stop wheel; independent means, initiated by said permutation code selecting mechanism in response to the

first code signal of a group, for starting an independent rotary movement of said rotatable member; and means for continuing said independent rotary movement through an arc of 180 degrees during the operating time of the first mentioned progressive rotary movement.

EDWARD E. KLEINSCHMIDT.
